Herbert G. Odell

HIS ATTORNEY

UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

ROCK-DRILL CENTRALIZER.

Application filed April 13, 1923. Serial No. 631,863.

To all whom it may concern:

Be it known that I, LEWIS C. BAYLES, a citizen of the United States, a resident of Easton, county of Northampton, State of Pennsylvania, have invented a certain Rock-Drill Centralizer, of which the following is a specification accompanied by drawings.

This invention relates to rock drills of the hammer type, but more especially to a centralizer for the drill steel.

The objects of this invention are to enable the drill steel to be maintained in the desired position on starting, when the drilled hole is to be made on an inclined surface in 15 the face of the wall.

Further objects of the invention will hereinafter appear, and to these ends the invention is shown in one of its preferred forms in the accompanying drawings, in which—

20 Figure 1 is a diagrammatic view in side elevation of a mounted rock drill, having the centralizer applied thereto, and

25 Figure 2 is a perspective view in an enlarged detail, of the centralizer applied to a rock drill.

Referring to the drawings, the rock drill A has the cylinder B, back head C' and front head D, into which the drill steel C extends for receiving the blows of impact of 30 the hammer piston. The rock drill A is slidably mounted in the channel or guide way E' of the shell E, and is adapted to be moved longitudinally by the feed screw F, which may be rotated by the handle G secured thereto. In this instance, the shell E of the rock drill is clamped to the cross bar H in any suitable manner. The cross bar H may be adapted vertically on the column J as desired.

40 On starting it is difficult to keep the bit K of the drill steel C at the desired point against the rock. It is therefore necessary to employ some means for maintaining the drill steel bit in the desired position on starting. In accordance with my invention, I provide a centralizer comprising a clamp O preferably having pivotally connected arms P and Q, the outer portions of which are adapted to encircle or embrace the drill

45 steel C, and guide the steel on starting a hole, as shown in Figure 2. The arms P and Q, which are in this instance pivoted together at R, are provided at their inner ends with the outwardly bent extensions S and

50 T respectively, which are adapted to slide

in channels or guide ways E' of the shell E. The inner portions of the arms P and Q are preferably adapted to be held in the guide ways E', and in this instance the arms extend at an angle to the longitudinal axis of the shell E. In order to force the arms into frictional engagement with the channels E', I provide a screw U threaded into the arm P and adapted to contact with the inner surface of the arm Q. By tightening the screw U against the inner surface of the arm Q, the arms will be forced outwardly into tight frictional contact with the parts V and W of the shell E.

The clamp O may be removed any time 70 after the hole in the rock L has been pointed or started, by loosening the screw U and sliding the outwardly bent extensions S and T from the channels or guide ways E'. This operation is, however, unnecessary as the 75 front head D of the drill will force the clamp O from the channels or guide ways E' after the drill A has been forced a sufficient distance forwardly by the feed screw F, and thereafter the clamp may be removed as desired.

It will readily be seen that by means of my centralizer a hole in an inclined surface of the rock can be quickly and easily pointed or started without the drill bit sliding or skipping thereover.

I claim:

1. In a rock drill, the combination with a shell having guide ways in which the rock drill carriage is adapted to move, of a centralizer for a drill steel comprising a pair of connected arms adapted to embrace the shank of a drill steel, and manually operable means for frictionally holding portions of said arms in said guide ways tending to hold said centralizer stationary relative to said shell.

2. A centralizer for drill steels comprising a clamp, having pivotally connected arms adapted to encircle the drill steel, outwardly bent extensions on the arms adapted to slide in the guide ways of a rock drill shell, and means for removably securing the clamp to the shell of a rock drill.

3. A centralizer for drill steels, comprising pivotally connected arms adapted to encircle the drill steel, outwardly bent extensions on the arms adapted to slide in the guide ways of a rock drill shell, and means for forcing the outwardly bent extensions

2
into tight frictional engagement with the shell of a rock drill.

4. In a rock drill, the combination with a shell of a centralizer for maintaining the drill steel in alignment with the machine, said centralizer comprising a clamp having pivotally connected arms adapted to encircle the drill steel, extensions on the arms adapted to slide in the said shell of the rock drill, and means for frictionally binding the clamp in the shell.

5. In a rock drill, the combination with a shell of a centralizer for the drill steel, comprising a clamp having pivotally connected arms adapted to encircle the shank of the drill steel and slide in the said shell of the rock drill, and a screw threaded into one

of said arms and adapted to contact with the other arm, whereby the shell may be gripped tightly by the clamp.

6. In a rock drill, the combination with a shell having guide ways, of a centralizer for the drill steel, comprising a clamp having pivotally connected arms adapted to encircle the shank of a drill steel, outwardly bent extensions on said arms adapted to slide in said guide ways and a screw threaded into one of said arms and adapted to bear against the other arm for holding said clamp in the guide ways of the shell.

20
